UNITED STATES PATENT OFFICE.

HARRY M. WELLS, OF BRIDGEPORT, CONNECTICUT, ASSIGNOR TO THE LOCOMOBILE COMPANY OF AMERICA, OF NEW YORK, N. Y.

DESIGN FOR AN UNDERFRAME FOR AUTOMOBILES.

SPECIFICATION forming part of Design No. 34,578, dated May 28, 1901.

Application filed January 12, 1901. Serial No. 43,077. Term of patent 14 years.

To all whom it may concern:

Be it known that I, HARRY M. WELLS, of Bridgeport, in the county of Fairfield and State of Connecticut, have invented and produced a new and original Design for an Underframe for Automobiles, of which the following is a specification.

My design relates to the underframe of an automobile vehicle and is illustrated in the accompanying drawing, representing a perspective view of an underframe.

The frame comprises side bars 1 1, a front cross-bar 2, projecting laterally beyond said side bars, and a rear cross-bar 3, also projecting laterally beyond said side bars and of substantially equal length with the cross-bar 2.

The novel features of my design are found in the conformation of the rear cross-bar 3 and are as follows:

4 4 are two straight lower struts in line with each other and separated by a space, and 5 is a bowed upper strut to which the side bars 1 1 are joined and which joins the lower struts 4 4 at or near the outer ends of the latter, the lower and upper struts 4 5 being in the same vertical plane.

6 is a U-shaped loop which is joined about midway of the legs of the U by the inner ends of the struts 4 4, and 7 is a substantially

straight strut connecting the ends of the legs of the U. From the ends of the strut 7 to the outer ends of the struts 4 4 extend two diagonal struts 8 8, which, with said strut 7, form substantially a bow. The U-shaped loop 6 and the struts 4 7 8 are all in the same horizontal plane. The struts 4 4, with the outer ends of the legs of the U, and the diagonal struts 8 8 form substantially two right-angled triangles, the struts 8 8 being the hypotenuses and the struts 4 4 the elongated bases of said triangles.

The characteristic feature is the design formed in a rear cross-frame by two bows in a vertical and a horizontal plane, respectively, each having a continuous arc, the two having a common chord interrupted by a U-shaped loop located in a horizontal plane and joining the arc of the horizontal bow.

I claim—

The design for an underframe for automobiles substantially as herein shown and described.

In testimony whereof I have affixed my signature in presence of two witnesses.

HARRY M. WELLS.
